UNITED STATES PATENT OFFICE.

FRANCIS KINGSLEY, OF NEW ROCHELLE, NEW YORK.

SHOE-POLISHING APPARATUS.

1,373,662.

Specification of Letters Patent.

Patented Apr. 5, 1921.

Application filed August 10, 1917. Serial No. 185,439.

To all whom it may concern:

Be it known that I, FRANCIS KINGSLEY, a citizen of the United States, and residing in the city of New Rochelle, in the State of 5 New York, have invented certain new and useful Improvements in Shoe-Polishing Apparatus, of which the following is a specification, reference being had to the accompanying drawings, forming a part hereof.

10 The general object of this invention is to reduce to a minimum the time required in the operation of polishing a pair of shoes and therefore to permit the maximum volume of work to be done with a given amount 15 of labor and in a given space.

By the present invention it is not sought to produce improved machines of a wholly automatic character but to produce apparatus, power-driven, which shall be capable 20 of being manipulated by the operator with such readiness and celerity that the time required for the operation is reduced to a minimum. In accordance with the invention a rotary brush, driven at a suitably high 25 speed, is so supported that it is capable not only of a free, swinging movement in every direction, in a horizontal plane, without material resistance, but also of free movement vertically without material resistance, so 30 that the operator, in the shortest possible space of time, may move the brush into contact with every portion of the surface to be polished. In order that the whole operation may be systematized to the last 35 degree and time saved to the last second, the whole apparatus is so arranged that the customer, either sitting or standing, places his foot upon the foot-rest without being required to turn about and the operator sits 40 or kneels or stands on the opposite side of the foot-rest with his back to the wall and with a power-driven brush, supported as above stated, for each hand, so that when the blacking or polishing material has been applied 45 to the shoe the operator can quickly apply the brushes, one at each side, to every part of the surface to be polished, including the top of the toe as well as the sides of the foot, the instep and the heel.

50 The invention will be more fully explained hereinafter with reference to the accompanying drawings in which it is illustrated and in which—

55 Figure 1 is a view in elevation illustrating the general arrangement of the apparatus.

Fig. 2 is a view, partly in vertical section and partly in elevation, on a larger scale than that of Fig. 1, showing more in detail the brush and its supporting and driving means.

As indicated in Fig. 1 a customer, stepping forward upon the platform *a* and resting his hands on the handrail *b*, places his foot upon the foot-rest *c*. The operator, seated upon a stool *d*, with his back to the wall *e*, manipulating with each hand a power-driven brush *f*, brushes the dust from the shoe and then with his hands, aided by other devices not shown, applies the 70 blacking or the polishing material to the shoe. The brushes are again manipulated by the operator to polish the blacking or polishing material which has been applied to the shoe, and with a few strokes of the polishing cloth the operation is completed.

75 It will be obvious that each brush (only one being shown in the drawings), must be capable of being moved freely toward and from the shoe and along the side of the 80 shoe and up and down, so that it may be brought into contact with every portion of the surface to be polished, and that it must also be so supported that it shall offer practically no resistance to any of such movements by the operator. In the most satisfactory embodiment of the invention thus far subjected to practical test, the brush *f* is provided not only with bristles *f'* which are radially disposed, but with bristles *f''* 90 on the end, which are normal to the plane of rotation. This brush is supported and driven by means which cause the brush to be rotated upon a substantially vertical axis and also permit it to be swung freely in a 95 substantially horizontal plane and to be raised and lowered freely. As shown, the brush is carried by a short inflexible shaft *g*, which is preferably connected by a universal joint *g'*, so as to give greater flexibility of movement, to another vertical shaft or shaft section *g''* which is arranged to telescope within a tubular shaft or shaft section *g'''*. The latter is connected at its upper end to the shaft *h'* of a motor *h*, 100 which is supported by a support *h''* which has a spherical bearing at *h'''* in a supporting bracket *h''*. A sleeve *i* depends from the support *h''* and has at its lower end a suitable bearing *i'* for the lower end of the 110 tubular shaft *g'''*. The latter is slotted longitudinally, as at *g''*, to coöperate with a

pin g^5 on the telescoping shaft section g^2 , so as to compel rotation of the shaft section g^2 with the shaft section g^3 while permitting relative vertical movement. The shaft section g is provided with a handle k , in order that the brush may be manipulated conveniently by the operator, the handle k having a sleeve k' to receive the shaft section g' . For the purpose of counterbalancing the weight of the brush and its connected shaft sections, a counterbalance spring l is connected at one end, as at l' , to the sleeve i , and at the other end to a hooked rod l^2 which engages the handle k and is guided in its vertical movement by guides i^2 on the sleeve i .

It will now be understood that in the use of the apparatus shown in Figs. 1 and 2 the operator, grasping the handle k , moves the brush f in contact with the surface of the shoe to be polished, swinging it toward and from the shoe and to and fro in contact with the side of the shoe, and then lifting and swinging it so that the bristles f^2 may contact with the upper surface of the shoe. Preferably the operator is provided with a similar brush for manipulation by each hand, so that the operation may be expedited, but as the means for supporting and operating the brushes are identical it is not necessary to describe and show them both.

I claim as my invention:

1. In an apparatus of the character described, the combination of a rotary brush, a vertical brush shaft movable with the brush in a horizontal and in a vertical plane, a depending drive shaft connected slidingly with the first named shaft and means to counter-balance the weight of the brush and the brush shaft for vertical movement relative to the drive shaft.

2. In an apparatus of the character described, the combination of a rotary brush, a drive shaft therefor, a nonrotary housing in which said shaft is supported, and a brush shaft connected through a telescoping joint with said drive shaft and movable in a horizontal and vertical plane.

3. In an apparatus of the character described, the combination of a rotary brush, a drive shaft therefor, a nonrotary housing in which said shaft is supported, a brush shaft connected through a telescoping joint with said drive shaft and movable in a horizontal and vertical plane, a spring to counter-balance the weight of the brush and the lower section of the telescoping shaft.

This specification signed this 6th day of August, 1917.

FRANCIS KINGSLEY.
